ERASE HEAD FOR A MAGNETIC TAPE RECODER OR SIMILAR ARTICLE

Paul H. Schulte, D-9 Gardenia, San Francisco, Urb.,
Rio Piedras, Puerto Rico

Filed Nov. 1, 1963, Ser. No. 77,251

Term of patent 3½ years

(Cl. D26—14)

FIG.1

FIG.5

FIG.2

FIG.4

FIG.3

FIG.6

FIG. 1 is a perspective view of an erase head for a magnetic tape recorder or similar article, showing my new design;

FIG. 2 is a front elevational view;

FIG. 3 is a rear elevational view;

FIG. 4 is a side elevational view, the opposite side being substantially a mirror image thereof;

FIG. 5 is a top plan view; and

FIG. 6 is a bottom plan view thereof.

I claim:

The ornamental design for an erase head for a magnetic tape recorder or similar article, substantially as shown and described.
